UNITED STATES PATENT OFFICE.

WARREN L. COLBY, OF PROVIDENCE, RHODE ISLAND.

DISPENSING DEVICE.

Application filed May 16, 1927. Serial No. 191,792.

The present invention relates to a device for dispensing one at a time soda straws and the like, and has for an object to provide a construction of container or hopper and delivering apparatus, which are so combined that they may receive an original container or package in which the straws are shipped, so that by merely making an incision or opening at the corner or side of the original packing, the latter may be fitted into the dispensing device and the feeding and operation will proceed without special manipulation or adjustment.

Another object of the invention is to provide a device of this kind which is operable by inserting the hand beneath the hopper to receive a straw, the hand displacing an operating lever or member and causing the device to operate and deliver the straws one at a time, each time the hand is inserted beneath the hopper.

Another feature of the present invention is to provide a device which may be operated from either side, and a device which is of extreme simplicity and utilizes but a single roller with a weighted or pendulum arm, the roller having an opening to receive a single, or two if desired, straw and arranged to project into the hopper or holder when in normal position.

With the foregoing and other objects in view, the invention will be more fully described hereinafter, and will be more particularly pointed out in the claim appended hereto.

In the drawings, wherein like symbols refer to like or corresponding parts throughout the several views,

Figure 1 is a front elevation of a dispensing device constructed according to the present invention.

Figure 2 is an end elevation of the same.

Figure 3 is an enlarged transverse section taken substantially centrally through the device and showing an original package of straws mounted therein.

Figure 4 is a similar view with the lid of the hopper or holder raised and showing the original package fitted or wedged into the cover, and

Figure 5 is a transverse section taken through the device showing the hand in position for operating the device to deliver a single straw.

Referring to the drawing 10 designates a base which may or may not be used and which in the present instance supports a pair of

spaced apart end plates 11, which at their lower ends are substantially of triangular contour. The intermediate portions of the end plates 11 are provided with integral discs or heads 12 of substantially circular construction and adapted to receive against their inner faces the opposite ends of a roller or cylinder 13. The pins 14, screws or the like are mounted centrally through the heads 12 and engage the opposite ends of the roller or cylinder 13 to support the roller and permit of its axial rotation. The roller 13 is held in a definite position by means of a plate 15 which is secured at 16 by screws or the like to the under side of the roller 13, and which extends radially from the roller, so that the plate 15 is adapted to normally hang downwardly and hold the roller 13 in a definite position of rest.

The roller 13 is provided in its upper side with a recess or cavity 17 extending throughout the length of the roller and of a size to receive one or more articles of predetermined size and length. In the present case the groove or recess 17 is of a size adapted to receive a single straw for use around soda fountains and the like so that the device may dispense the straws one at a time.

Arranged diagonally over the roller 13 is a hopper or support 18 in the form of a substantial rectangular box-like body with its lower edge cut away as at 19 and sufficiently to receive the upper portion of the roller 13 therein, so that straws disposed in the support 18 may freely roll into the groove 17 of the roller and be carried exteriorly of the support 18 when the roller 13 is turned. The upper portion of the support 18 is in the form of a lid 20 hinged at 21 at one side of the support 18 and provided at its other side with a handle 22 by means of which the lid may be swung upwardly into the position, shown in Figure 4. The ends 23 of the holder or hopper 18 preferably comprise continuations of the end members 11, while the ends 24 of the cover 20 are separate triangular sections, which are fitted in the angularly constructed cover.

The cover 24 provides one-half of a rectangular body, while the holder 18 forms the other half of the rectangular body. The lid and the support 18 may, of course, be changed in form and proportions to accommodate the device to different conditions of use. In the present instances the rectangular construction is resorted to as this form of the invention is adapted to receive and support a rectangular container 25, which is of paper or the

like, and which comprises the original package in which soda straws 26 are placed, so that the straws 26 are protected in the original package from contact with the hand, 5 dust or the like. The original package 25 is of such size that it fits snugly in the lid 20 of the device, as shown in Figure 4, so that when the lid 20 is raised the package 25 is lifted therewith. The end walls 24 of the lid 10 bind against the opposite ends of the container 25 and assist in maintaining the container in the lid. The lower corner of the original package or container 25 is cut away, as at 27 in any suitable formation, so as to permit 15 the free and easy passage of the straws downwardly through the opening 27 and against the roller 13 of the device. In this manner, the straws come in contact only with the roller 13 directly from the original package. As shown in Figure 5, when the operator projects the hand beneath the roller 13, the tips of the fingers engage the plate 15 and swing the same with the roller to one side, so as to turn the roller and bring the 20 slots 17 to the outer side of the hopper or support 18 and toward the palm of the hand. While, in this position, shown in Figure 5, the straw is permitted to roll out of the recess or groove 17 by gravity and fall into the 25 hand. The hand is now withdrawn with the single straw and the plate 15 swings back into vertical position and turns the roller 13 into its normal position with the groove 17 uppermost to receive a second straw. It is apparent 30 that this operation may be carried out from either side of the device by merely resting the hand beneath the roller 13 from either side, because the plate 15 and roller 13 are so mounted that they may swing in 35 either direction and there is a clearance left at each side of the holder 18 for the hand.

Although I have illustrated and described

the invention in connection with one particular form of package it will be understood that it is equally applicable to packages of any 45 form the holder for the package being altered accordingly.

It is obvious that various changes and modifications may be made in the details of construction and design of the above specifically described embodiment of this invention without departing from the spirit thereof, such changes and modifications being restricted only by the scope of the following claim:

What is claimed is:—

A dispensing device comprising a diagonally disposed hopper comprising a stationary lower part and a lid upper part with said parts of angular formation, a rectangular original package of straws adapted to be 50 tightly fitted into the lid part and to be opened at its exposed corner for releasing the straws in the original container, said lid with the container adapted to be swung down into closed position for housing the container and disposing the open edge thereof lowermost, a roller mounted in the lower part of the enclosing body for engaging the released straws and having a groove therein for receiving a predetermined number of the 55 straws at a time, a finger plate secured to the roller and extending downwardly therefrom for maintaining the roller in a definite normal position with the groove uppermost, said plate adapted to be swung by the hand 60 to turn the roller when the hand is pushed into position beneath the roller, said roller in turning adapted to liberate said predetermined number of straws from the body portion and deposit the straws in the hand disposed beneath the roller.

In testimony whereof I affix my signature.

WARREN L. COLBY.
